UNITED STATES PATENT OFFICE.

JOHN R. McDOWELL, OF AUBURN, INDIANA.

SPARK-PLUG.

1,089,244.

Specification of Letters Patent.

Patented Mar. 3, 1914.

Application filed May 24, 1912. Serial No. 699,442.

To all whom it may concern:

Be it known that I, JOHN R. McDOWELL, a citizen of the United States, residing at Auburn, in the county of Dekalb and State 5 of Indiana, have invented new and useful Improvements in Spark-Plugs, of which the following is a specification.

This invention relates to spark plugs, the object in view being to provide a spark plug 10 having two decided points of advantage, the first of which is to prolong and extend the spark as it jumps between the points, and secondly to provide for a ready cleaning away of any matter which may accumulate 15 between the points of the plug, the cleaning away of such material being effected by the explosion or rapid movement of the gases in the combustion space of the cylinder, in connection with which the plug is 20 used.

With the above and other objects in view, the invention consists in the construction, combination and arrangement of parts, as will be hereinafter more fully described, 25 illustrated in the accompanying drawings, and pointed out in the claim hereunto appended.

In the drawings: Figure 1 is a side elevation of a spark plug, embodying the present invention. Fig. 2 is an end view, looking 30 toward the sparking points thereof. Fig. 3 is a longitudinal section through the spark plug, taken in line with the igniter points.

35 Referring to the drawings, 1 designates the outer metal jacket of the spark plug, and 2 the usual confining plug which is threaded in the outer end of the main body of the plug, for the purpose of holding the 40 core in place therein.

3. designates the core which is usually made of porcelain or other good insulating material, the same being provided with a 45 positioning flange 4, against which the con-

fining plug 2 bears, when the parts of the plug are brought into their final assembled 50 positions. Extending lengthwise through the core 3 is the wire 5 which terminates at one end in the live or spark point 6, and at the other end in the binding post 7.

In the preferred embodiment of this invention, an igniter point 8 extends inward from the metal jacket 1, although such 55 point 8 is not essential, as the casing itself may be used as the outer spark point.

In carrying out the present invention, I

locate a dead point 9 between the spark point 5 and the outer shell or jacket, thus causing a double spark, or in other words, causing the spark to jump in two places 60 between the spark point and the dead point, and between the dead point and the outer shell or casing. This has the effect of making two sparks, or in other words, a spark of double length, thus adding materially 65 to insure the igniting of the charge contained in the combustion space of the cylinder. Furthermore, the dead point, it will be observed, is concaved or recessed on both sides, so that the outer extremity thereof is 70 larger in diameter and size than any other part, causing the spark to jump across the smallest space which is at the extremity of the dead point. Correspondingly, the spark point is concaved or recessed on the side 75 next to the dead point, which is for the same purpose as that recited in connection with the dead point, namely, to carry the spark to the outermost extremity of the spark point and the dead point. I do not limit 80 myself to any particular number of dead points, as quite a number may be located between the spark point and the outer casing, or in other words, between the spark point carried by the porcelain core and the outer 85 shell or jacket. By using a greater number of these dead points, the spark may be prolonged or extended to a very considerable extent, and by concaving or recessing the dead points on opposite sides, any material, 90 such as carbon, which may accumulate between the points will be blown out by the rapid movement of the gases in the explosion in the combustion chamber. Furthermore, it has been found in practice that the 95 spark in its second jump, or in other words, after leaving the dead point is more intense than in the initial jump before it reaches the dead point.

The inner end of the core is provided with 100 a central conical recess, as shown at 10, so as to give clearance around the ignition points and prevent danger of corrosion of the points themselves. This recess will also materially assist in breaking up any carbon deposit on the extremities of the points. For a like purpose the outer edge of the inner end of the plug is beveled, forming a 105 V-shaped annular ridge from the apex of which the dead point 9 projects, said dead point being located in radial line between the igniter joint and jacket. Furthermore,

should matter accumulate between two of the points, so as to prevent the jumping of such spark at such place, the spark will still jump across the points between which there is no obstructing matter.

What is claimed is:

A spark plug, comprising a metal jacket, an insulating core therein having the inner end thereof formed with a central recess and its outer edge beveled, leaving a V-shaped annular ridge, a spark point protruding from the core centrally of said recess and partially arranged in said recess,

and a dead point projecting from the apex of said ridge and lying in a radial line 15 between the spark point and the jacket, the dead point being concaved on both sides back of the extremity thereof and the spark point being concaved on the side next to the dead point.

In testimony whereof I affix my signature in presence of two witnesses.

JOHN R. McDOWELL.
